(57) **CLAIM**

The ornamental design for a three-in-one wireless charger as shown and described.

DESCRIPTION

FIG. 1 is a front, left and top perspective view of a three-in-one wireless charger, showing our design.

FIG. 2 is a rear, right and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is another front, left and top perspective view of the three-in-one wireless charger in a usable state.

FIG. 10 is another front, left and top perspective view of the three-in-one wireless charger in a second usable state.

FIG. 11 is another front, left and top perspective view of the three-in-one wireless charger in a third usable state.

FIG. 12 is another front, left and top perspective view of the three-in-one wireless charger in a fourth usable state; and, FIG. 13 is another front, left and top perspective view of the three-in-one wireless charger in a fifth usable state.

The dashed broken lines depict portions of the three-in-one wireless charger that form no part of the claimed design.
